WINDOW SASH

David E. Ross, La Fayette, Ind., assignor to Ros-
tone, Incorporated, La Fayette, Ind., a corpora-
tion of Indiana

Original application July 18, 1932, Serial No.
623,266. Divided and this application January
3, 1933. Serial No. 649,981

7 Claims. (Cl. 189—76)

This application is a division of my applica-
tion filed July 18, 1932, Serial No. 623,266, and is
for a novel glazed metallic sash and weather
stripping therefor.

5 The objects of the invention are to provide
a window sash having great rigidity, weather-
proof and soundproof, and which will enable
100% of the window opening to be utilized if
so desired.

10 I will first explain the invention with reference
to the accompanying drawing which illustrates
one practical embodiment thereof, and then
summarize in the claims the essential features
of construction and novel combination of parts
15 for which protection is desired.

In said drawing:—

Fig. 1 is a front view partly broken away of
a window frame equipped with a glazed sash
embodying the invention.

20 Fig. 2 is a view of the glazed metal sash de-
tached and partly in section.

Fig. 3 is a top view of Fig. 2.

Fig. 4 is a transverse section through Fig. 2.

Fig. 5 is an enlarged detail sectional view of
25 the sash weather stripping devices on line 5—5
Fig. 2.

Fig. 6 is an enlarged section on the line 6—6,
Fig. 1.

The construction of the novel sash is based
30 upon the well-known rigidity of heavy glass.
Preferably I use a sheet 1 of plate glass approxi-
mately $\frac{1}{4}$ " thick and of a size approximating
the desired glazed window opening. This plate
35 is enclosed in a frame consisting of opposite
side bars 2 and 3 connected by rod bolts 4, 4'.
Bar 2 has a channel in one side into which one
edge of the plate 1 is inserted, and at the bottom
of the channel there is a resilient member 2r,
40 preferably of plastic or non-oxidizing rubber.
On the outer side of bar 2 a rack 2n is preferably
provided to enable the sash to be operated by
a gear 20 as hereinafter described.

The bar 3 at the other end of the plate is
grooved to receive the edge of the plate, and a
45 resilient member 3r similar to 2r is inserted in
the groove. The rod bolts 4, 4' connect the
bars 2 and 3 and cause them to securely clamp
the glass plate therebetween.

The glass plate 1 will not warp or sag, and is
50 tightly clamped between the bars 2 and 3. The
resilient liners 2r, 3r allow for unequal coeffi-
cients of expansion between the metal frame
and the glass.

The bar 2, being very long in comparison to
55 its thickness and breadth, cannot possibly get

diagonal and "cock" and it has an easy sliding
fit in the ways for ease of manipulation; while
the bar 3 preferably does not touch the sides
of the ways. The sash structure can be made
weather proof in the frame as hereinafter de-
60 scribed. These metal sashes are preferably
mounted in a metal frame 5 as described in my
aforesaid application and as the glazed metal
sash are very narrow, a number of such sashes
(Fig. 6) can be readily assembled within a nar-
65 row frame.

Disposed over the upper edge of each sash is
a tubular member 14 of any suitable material
which is adapted to fill the space between the
70 housing sheets c, c' as described in my aforesaid
application and thus form an absolute weather
stripping and soundproofing medium. Within
this tube 14 is placed a resilient liner to hold it
concentric, and to allow for the unequal coeffi-
cients of expansion of the metals to the glass.
75

To the inner face of the guides 7 between the
sash (as described in my said application) may
be attached bowed metal strip 7x (see Fig. 6), the
edges of which may contact with the glass and
act as weather stripping to exclude air and mois-
80 ture from the interior of the guide.

In the construction shown, at the bottom of
the sash a weather strip 15 is bent around the
85 rod 4' (see Fig. 5). This strip is of spring ma-
terial which has two lines of contact with the
glass, as shown in Fig. 5. Welded to strip 15 is a
curved strip 16, which may have fingers 16' on
its outer edge. Strip 16 is also of spring material
but heavier than strip 15. This holds the strip
15 rigidly against the glass. The strip 16 may
90 be fastened to the strip 15 by welding or braz-
ing; and the stiff fingers 16' extend up on the
glass to hold the strips in position. This permits
rain water to drip off and not collect or freeze
and rupture the structure. The weather strip-
ping is highly efficient and prevents any trans-
mission of outside atmosphere past the glass area
and there is a multiple seal to prevent conduction
of either atmospheric or weather conditions from
95 without to within.

The whole sash is supported by or hangs on part
2, which is the actuating member when it is
vertically lifted, and the hinged member when
it is used for a casement window (not shown).
It is obvious that if the gear teeth or rack 2n
105 on bar 2 were omitted and hinges substituted
this assembly could be operated as a casement
window.

The sash may be raised or lowered by hand
110 or any suitable mechanism. I have shown means

for operating the sash by means of a pinion 20
engaging the rack bar 2. The device for operat-
ing the pinion forms the subject-matter of my
companion application filed August 15, 1932
5 Serial No. 628,947.

The window sash can be shipped from the
factory ready for installation and operation.

I claim:—

- 10 1. A glazed metal sash comprising a glass plate,
bars at opposite ends of the plate and tie rods
connecting the bars and causing them to clamp
the plate between them, the plate giving rigidity
to the structure.
- 15 2. A sash as set forth in claim 1, having cush-
ioning members interposed between the bars and
the edges of the glass plate.
- 20 3. A glazed metal sash comprising a glass plate,
grooved metal bars at opposite ends of the plate,
and tie rods connecting the bars above and be-
low the plate and causing them to clamp the
plate between them; the glass plate forming a
separating and distending member preventing
sagging of the sash.
- 25 4. In a sash as set forth in claim 3, cushioning
members interposed between the grooved bars
and the edges of the glass plate.
5. A glazed metal sash comprising a glass plate,
grooved metal bars at opposite ends of the plate,

tie rods connecting the bars above and below
the plate and causing them to clamp the plate be-
tween them, said glass plate forming a separat-
ing and distending member preventing sagging
of the bars and bolts, and cushioning members
interposed between the grooved bars and the
edges of the glass plate.

6. A glazed metal sash comprising a glass plate,
grooved metal bars at opposite ends of the plate,
tie rods connecting the bars above and below the
plate and causing them to clamp the plate be-
tween them, said glass plate forming a separat-
ing and distending member preventing sagging
of the bars and bolts, and weather strip-
ping attached to the top and bottom of the sash.

7. A glazed metal sash comprising a glass plate,
grooved metal bars at opposite ends of the plate,
tie rods connecting the bars above and below the
plate and causing them to clamp the plate be-
tween them, said glass plate forming a separat-
ing and distending member preventing sagging
of the bars and bolts, a curved metal strip at-
tached to the lower rod and engaging one face
of the glass plate, a curved strip connected with
the first strip and engaging the opposite side of
the glass plate; and a curved strip attached to
the upper rod.
